On Behalf of
 G. H. Knight & interests

Addis E. Chamberlain for Knight & sons atty.

Des. 1705

A. C. Chamberlain of Cincinnati, Ohio.

Assignor to Chamberlain & Co.

Letter Patent No. 1705. Dated Jan'y 27, 1863.

The schedule referred to in this Letter Patent and making part of the same.

To all whom it may concern;

Be it known that I, Adelis C. Chamberlain of Cincinnati, in the County of Hamilton and State of Ohio have invented and produced a new Ornamental Design for a Cannon or (Hall) Stove called the "Chief"; and I, hereby declare the annexed drawing, making a part of this specification, to be an accurate representation of my said design.
I claim herein as new and of my invention.

2

Dec. 1705

and desire to secure by letter of patent,

The design for a Brown Stone called "Cobley" as represented in the

Sketching of which I enclose, I enclose set-my hand.

James
Geo. H. Bright
Egg. O. N. Bush,

A. E. Chamberlain
